UNITED STATES PATENT OFFICE

121,824

DESIGN FOR A MILLING MACHINE KNEE

Glenn W. Tamm, Chicago, Ill., assignor to
Kearney & Trecker Corporation, West Allis,
Wis., a corporation of Wisconsin

Application May 29, 1940, Serial No. 92,673

Term of patent 14 years

To all whom it may concern:

Be it known, that I, Glenn W. Tamm, a citizen of the United States, residing at Chicago, in the county of Cook and State of Illinois, have invented a new, original, and ornamental Design for a Milling Machine Knee, of which the following is a specification, reference being had to the accompanying drawings, forming part thereof.

Figure 1 is a view in perspective of a milling machine knee, showing my new design;

Figure 2 is a view in front elevation of the milling machine knee shown in Fig. 1; and

Figure 3 is a view in side elevation thereof.

I claim:

The ornamental design for a milling machine knee, substantially as shown.

GLENN W. TAMMEN.
